UNITED STATES PATENT OFFICE.

EMERALD E. JONES, OF CHICAGO, ILLINOIS, ASSIGNEE TO SURTY GUARD COMPANY,
OF CHICAGO, ILLINOIS, A CORPORATION OF ILLINOIS.

BELT-SHIFTER.

1,399,388.

Specification of Letters Patent.

Patented Dec. 6, 1921.

Application filed January 22, 1921. Serial No. 439,098.

To all whom it may concern:

Be it known that I, EMERALD E. JONES, a subject of the King of Great Britain, and a resident of the city of Chicago, county of 5 Cook, and State of Illinois, have invented certain new and useful Improvements in Belt-Shifters, of which the following is a specification.

My invention relates to belt shifters of the 10 general type shown by Letters Patent of the United States, No. 1,161,775, granted on my application on November 23, 1915, and it has for its object the provision of improved means for operating the shifting mechanism 15 whereby a more completely controlled and more positively acting structure may be obtained.

Other objects will appear hereinafter.

The invention consists in the combinations 20 and arrangements of parts hereinafter described and claimed.

The invention will be best understood by reference to the accompanying drawings forming a part of this specification, and in 25 which,

Figure 1 is a side view of my improved mechanism applied in position for shifting a belt;

Fig. 2 is an end view of the mechanism as 30 seen from the left in Fig. 1;

Fig. 3 is an enlarged detail view, being a section taken on line 3—3 of Fig. 1;

Fig. 4 is an end view of the mechanism as 35 seen from the right in Fig. 1;

Fig. 5 is a cross section taken substantially on line 5—5 of Fig. 1 but with certain of the parts in changed position;

Fig. 6 is a view of the parts shown in Fig. 5 as seen from above in said figure; and 40

Fig. 7 is a section taken on line 7—7 of Fig. 6.

Referring to the several figures of the drawings, 10 indicates a driving pulley fixedly mounted upon a line shaft 11 revolvably 45 supported in position a short distance below the ceiling of a shop or factory, the pulley being operatively connected by means of an endless belt 12 with any suitable machine (not shown) which it is desired to drive. 50 As is shown in Fig. 1, there is no idler pulley arranged adjacent to the driving pulley 10 upon which the belt 12 may be slipped for discontinuing the driving operation, and it is to the supplying of this want that my 55 invention is directed.

As is shown in Fig. 1, my improved device comprises frames at opposite sides of the belt 12, such frames being supported in adjustable position from the ceiling, and being connected by a plurality of cross bars as 60 hereinafter described in detail. Two belt shifting members are movably mounted between the frames so as to be slid along the cross bars, one of the belt shifting members being opposite one edge of the belt and the 65 other being opposite the other edge. Means is provided for actuating the shifting members for engaging the edge of the belt on one side or the other for moving the belt 70 edgewise, belt supporting means being provided upon one of the frames for supporting the belt at one side of the driving pulley 10.

Coming now to a detailed description of my improved mechanism, 13 and 14 indicate posts depending from the ceiling at one side 75 of the driving pulley 10, such posts having adjustable connection with a curved frame bar 15 upon the inner face of which there are mounted a plurality of rollers 16 in position to receive the belt 12 thereon and to support the belt when it is moved toward the left from its position upon the driving pulley 10, as shown in Fig. 1. Upon the bar 15, I have provided a bracket 17, from 80 which extend two short rods 18 in parallel position supporting upon their outer ends a bracket 19; and upon the lower end of the curved bar 15, I have provided a second plate or bracket 20 adjustably mounted in position.

At the opposite side of the driving pulley 90 10, I have provided a post 21 depending from the ceiling and having a bracket 22 adjustably mounted thereon, the adjustable connection between the post 21 and the bracket being effected by the use of adjustable sleeves or collars 23. Adjustably connected to the lower end of the bracket 22, 95 I have provided a bracket 24, the bracket 24 being mounted by means of two pairs of adjustable sleeves and an interposed connecting rod 25. By the provision of the adjustable connections between the several frame members as above described, the parts of the frame are capable of being adjusted to meet varying conditions. As is clearly 100 shown in Fig. 1, the bracket 22 is disposed directly opposite the bracket 19, being connected therewith by means of cross bars 26, and the bracket 24 is disposed directly opposite the bracket 20, such brackets being 110

connected by means of two cross bars 27. By the provision of the adjustments as above described, the position of the cross bars 26 and 27 can be regulated to suit the position 5 of the belt.

Slidably mounted upon the bars 26, I have provided a carriage or slide block 28 which is provided upon its inner face with a spool or roller 29 revolvably mounted in position 10 thereon opposite the edge of the belt 12. Upon its outer face, the slide block 28 is provided with a small pulley 30, as is shown in dotted lines in Fig. 1. Slidably mounted upon the bars 27, I have provided a second 15 carriage or slide block 31 which is provided upon its inner face with a spool or roller 32 mounted opposite the other edge of the belt 12. Upon its outer face the slide block 31 is provided with a pulley 33, as will be 20 described hereinafter.

For controlling the position of the slide block 31, I have provided a latch member 34 pivotally mounted upon the outer face of the block (see Fig. 5), the operative end 25 of the latch being provided with a pin 35 adapted to engage one of the notches 36 provided in the bar 27 as shown in Fig. 1, the end of the latch 34 opposite that in which the pin 35 is mounted being equipped with 30 a coiled spring 37 which holds the pin 35 yieldingly in contact with the rod 27. Pivotally mounted upon the slide block 31 (see Fig. 7) I have provided a lever or arm 38 the end of which is beveled, as is best shown 35 in Fig. 5, for operative engagement with a diagonally disposed face of the latch 34. As will be readily understood from reference to Fig. 5, when the bar 38 is given a movement toward the left in that figure, the 40 pin 35 is lifted out of contact with the bar 27 against the action of the spring 37. The arrangement is such that upon a movement of the slide block 31 to the limit of its motion toward the left in Fig. 1 into contact 45 with a collar 39 on one of the bars 27, engagement of the pin 35 with one of the notches 36 serves to hold the slide block against movement in the reverse direction until the latch 34 has been operated by means 50 of the lever 38 or in some other suitable manner for releasing the latch from operative engagement with the rod 27. As is best shown in Fig. 6, the pulley 33 above referred to, is revolvably mounted upon a plate 55 or clip 40 carried by the arm 38 and movable therewith.

For manipulating the slide blocks 28 and 31, I have provided the framework with a plurality of idler pulleys for accommodating and controlling flexible cords or cables 60 for applying power to said slide blocks. As is shown in Fig. 2, a cable 41 provided with a handle 42 is suspended in convenient position from a pulley 43 over which the cable 65 extends. From the pulley 43, the cable ex-

tends to a second pulley 44, downwardly from which the cable leads to a pulley 45 revolvably mounted upon the bracket 19. From the pulley 45, the cable extends to a pulley 46, thence about the pulley 33 upon 70 the slide block 31, thence about a pulley 47 carried by the bracket 20, about pulleys 48 and 49 carried by the bracket 19, and thence to the slide block 28, to which the end of the cable is connected. Upon a downward pull 75 on the cable 41, force is applied to both of the slide blocks 28 and 31, as will be readily understood, the force applied to the block or carriage 31 being normally twice that applied to the block or carriage 28, by reason 80 of the two-ply engagement between the cable and the block 31 through the medium of the pulley 33 as compared with the single-ply engagement between the cable and the block 28. By the use of a movable pulley 85 engagement between the cable and one of the blocks and the fixed connection between the cable and the other block, a differential effect is produced in the application of power to the slide blocks through the medium of the cable 41. 90

For moving the slide blocks in the opposite direction, I have provided a second cable 50 provided with a handle 51 in convenient position for the operator, such cable depending from a pulley 52 mounted upon the ceiling. From the pulley 52, the cable extends to and over a pulley 53, thence downwardly over two pulleys 54 and 55 carried by the bracket 22 (see Fig. 4) thence about the 100 pulley 30, back to a pulley 56 carried by the bracket 22, thence over a pulley 57, and from there over a pulley 58 carried by the bracket 24 and to the slide block 31 where it is connected by means of an eye 59 with 105 the arm or lever 38 (see Fig. 1). By the provision of the two-ply engagement of the cable 50 with the slide block 28 and the single-ply connection of said cable with the slide block 31, a differential application of 110 power to the slide blocks is brought about, in the manner above described.

With the belt 12 in position upon the driving pulley 10, when it is desired to stop the operation of the driven machine, the operator exerts a downward pull upon the handle 42. The slide block 31 is first moved toward the left, until the spool 32 comes in contact with the edge of the belt, by which the resistance to the movement of the block 31 toward the left in Fig. 1 is increased. The slide block 28 is then moved to the limit of its motion toward the left in said figure, after which a continued downward pull upon the cable 41 serves to cause the slide 125 block 31 to move toward the left, forcing the belt 12 out of engagement with the driving pulley 10 into position upon the rollers 16 which constitute the belt supporting means carried by the curved frame bar 15. When 130

the slide block 31 reaches the limit of its motion toward the left in said Fig. 1, the latch 34 is moved into latching engagement with the rod 27 as above described, serving to prevent the slide block from moving again toward the right in that figure until a subsequent release of the latching member 34. In this manner, the belt 12 is prevented from returning into position upon the driving pulley 10 until the operator is ready for a renewed operation of the machine being driven. When it is desired to return the belt 12 to operative position upon the driving pulley, this result is effected by a downward pull upon the handle 51. The first result is the application of pressure upon the edge of the belt by the spool or roller 29. When the movement of the spool 29 toward the right in Fig. 1 is stopped by reason of engagement 20 of the opposite edge of the belt with the spool or roller 32 which is latched in position, the force of the cable 50 upon the lever 38 is increased, serving to release the latch 34, as above described, for permitting the 25 movement of the slide blocks and the belt toward the right in Fig. 1 for bringing the belt again into operative position upon the driving pulley 10.

By reason of providing an enlargement at 30 the outer end of each of the rollers 16, as is best shown in Fig. 3, the tendency of the belt 12 to shift into position upon the pulley 10 is materially decreased, whereby the locking effect of the latch 34 and the pin 35 is rendered ample in every way.

While I have illustrated and described the preferred form of construction for carrying my invention into effect, this is capable of variation and modification without departing from the spirit of the invention. I, therefore, do not wish to be limited to the precise details of the construction set forth, but desire to avail myself of such variations and modifications as come within the scope 45 of the appended claims.

Having described my invention, what I claim as new and desire to secure by Letters Patent, is:

1. A belt shifter comprising two frames 50 positioned on opposite sides of a belt, means carried by one of said frames for supporting the belt, a pair of bars interposed between said frames, a slide block movably mounted on said bars, a roller revolvably mounted on 55 said slide block opposite one edge of the belt, and means for moving said slide block for pushing said belt into position on said belt supporting means.

2. A belt shifter comprising two shifting 60 members mounted on opposite sides of the belt near one end portion and movable independently of each other transversely of the belt, and means for moving said shifting members in the same direction independently 65 of any movement of the belt.

3. A belt shifter comprising two shifting members mounted on opposite sides of the belt near one end portion and movable independently of each other transversely of the belt, means adapted positively to move said shifting members in the same direction independently of any movement of the belt, and other means adapted positively to move said shifting members in the opposite direction also independently of any movement of the belt. 70

4. A belt shifter comprising two shifting members mounted on opposite sides of the belt near one end portion and movable independently of each other transversely of the belt, and means adapted positively to move one of said shifting members in one direction for shifting the belt transversely and adapted positively to move the other shifting member in the same direction independently of the movement of the belt. 80

5. A belt shifter comprising two shifting members mounted on opposite sides of the belt near one end portion and movable independently of each other transversely of the belt, and a cable having operative engagement with each of said shifting members adapted to give them a positive movement in the same direction transversely independently of any movement of the belt. 90

6. A belt shifter comprising two shifting members mounted on opposite sides of the belt near one end portion and movable independently of each other transversely of the belt, and a cable having operative engagement with both of said shifting members adapted positively to move one member toward the belt and the other member in the direction away from the belt, said cable being arranged to have a differential effect upon said two members. 100

7. A belt shifter comprising two shifting members mounted on opposite sides of the belt near one end portion and movable independently of each other transversely of the belt, and two cables each having operative engagement with both of said shifting members for moving the members in the same direction and each arranged to have a differential effect upon said members, one 110 of said cables having the greater effect upon one of said members and the other cable having the greater effect upon the other member.

8. A belt shifter comprising a framework; two shifting members mounted on said framework on opposite sides of a belt and movable transversely of the belt independently of each other; a plurality of idler pulleys on said framework; a pulley connected with one of said shifting members; and a cable connected to the other of said shifting members and passing about one of said idler pulleys, passing thence about the pulley on said shifting member, and 120

passing thence about another of said idler pulleys, for moving both of said shifting members.

9. A belt shifter comprising a framework; two shifting members mounted on said framework on opposite sides of a belt and movable transversely of the belt independently of each other; a plurality of idler pulleys on said frame at each side of said belt; 5 a pulley connected with each of said shifting members; a cable connected to one of said shifting members and passing about one of said idler pulleys, passing thence about the pulley on the other of said shifting members, and passing thence about another of said idler pulleys, for moving both of said shifting members in one direction; and a second cable connected to the other of said shifting members and passing therefrom about one of said idler pulleys, passing thence to another of said idler pulleys, for moving both of said shifting members in the opposite 20 site direction from that in which said first named cable moves the said members.

10. A belt shifter comprising two frames positioned on opposite sides of a belt, means carried by one of said frames for supporting the belt, a bar interposed between said frames, a belt shifting member slidably mounted on said bar, a cable in engagement with said member for moving it along said bar, and a second cable in engagement with 30 said member and having a differential effect thereon for moving it in the opposite direction along said bar.

11. A belt shifter comprising two frames positioned on opposite sides of a belt, means carried by one of said frames for supporting the belt, a bar interposed between said frames, a belt shifting member slidably mounted on said bar, a cable having a single-ply connection with said shifting member 40 for moving it in one direction, and a second cable having a double-ply differential connection with said member for moving it in the opposite direction.

12. A belt shifter comprising a curved frame member, means for adjustably supporting said frame member at the side of a driving pulley, belt supporting means carried by said frame member, a second frame member adjustably mounted on said first 50 named frame member, a belt shifting member movable with respect to said frame opposite the edge of a belt passing over said pulley, and means arranged for moving said belt shifting member transversely with respect to the belt in the adjusted position of said second frame member.

13. A belt shifter comprising a curved frame member, means for adjustably supporting said frame member at the side of a 60 driving pulley, belt supporting means carried

by said frame member, a second frame member adjustably mounted on said first named frame member, a belt shifting member movable with respect to said frame opposite the edge of a belt passing over said pulley, an 70 idler pulley carried by said first named frame member on a transverse axis, a second idler pulley on said second frame member, and a cable having operative engagement with said pulleys in the adjusted positions 75 of said second frame member and having operative engagement with said belt shifting member for moving the belt from the pulley into position on the belt supporting means carried by said first named frame 80 member.

14. A belt shifter comprising a curved frame member, a plurality of depending supports adjustably connected with said frame member for supporting it at the side 85 of a driving pulley, belt supporting means carried by said frame member, a second frame member adjustably mounted on said first named frame member, a belt shifting member movable with respect to said frame 90 opposite the edge of a belt passing over said pulley, and means arranged for moving said belt shifting member transversely with respect to the belt in the adjusted position of said second frame member. 95

15. A belt shifter comprising a curved frame member, means for adjustably supporting said frame member at the side of a driving pulley, belt supporting means carried by said frame member, a second frame 100 member adjustably mounted on said first named frame member, a plurality of other frame members adjustably connected together, means for adjustably supporting said last named frame members at the opposite 105 side of said driving pulley, a belt shifting member movably mounted between the frame parts at opposite sides of the driving pulley and adapted to be positioned by the adjustment of said frame members in position opposite the edge of the belt passing over said driving pulley, and means arranged for moving said belt shifting member transversely with respect to the belt. 110

16. A belt shifter comprising a shifting member mounted opposite the edge of a belt and movable transversely thereof, tackle for moving said shifting member toward said belt for moving the belt edgewise, and automatically acting means on said shifting member for holding same against a return movement away from the belt. 115

17. A belt shifter comprising a shifting member mounted opposite the edge of a belt and movable transversely thereof, tackle for 120 moving said shifting member toward said belt for moving the belt edgewise, automatically acting means on said shifting member for holding same against a return movement away from the belt, and means 125

for releasing said shifting member and for moving it in the direction away from the belt.

18. A belt shifter comprising a frame located opposite one edge of a belt, a shifting member movably mounted on said frame, means on said frame for supporting said belt thereon, tackle for moving said shifting member for moving the belt into position on said supporting means, and automatically acting means on said shifting member for holding same against movement away from the belt serving to prevent the belt from moving out of engagement with said supporting means.

19. A belt shifter comprising a frame located opposite one edge of a belt, a shifting member movably mounted on said frame, means on said frame for supporting said belt thereon, tackle for moving said shifting member for moving the belt into position on said supporting means, automatically acting means on said shifting member for holding same against movement away from the belt, and means for releasing said holding means and for moving the shifting member in the direction away from the belt.

20. A belt shifter comprising a frame located opposite one edge of a belt, a shifting member movably mounted on said frame, means on said frame for supporting said belt thereon, means for moving said shifting member for moving the belt into position on said supporting means, automatically acting means on said shifting member for holding same against movement away from the belt, a lever on said shifting member adapted by a stroke in one direction to release said holding means for permitting said shifting member to move in the direction away from the belt, and means for giving said lever an operative stroke for releasing said holding means and for moving the shifting member in the direction away from the belt.

21. A belt shifter comprising a frame located opposite one edge of a belt, a shifting member movably mounted on said frame,

means on said frame for supporting said belt thereon, tackle for moving said shifting member for moving the belt into position on said supporting means, and a spring pressed latch on said shifting member adapted automatically to hold same against movement away from the belt serving to prevent the belt from moving out of engagement with said supporting means.

22. A belt shifter comprising a frame located opposite one edge of a belt, a shifting member movably mounted on said frame, means on said frame for supporting said belt thereon, means for moving said shifting member for moving the belt into position on said supporting means, a spring pressed latch adapted automatically to hold said shifting member against movement away from the belt, a lever adapted by a stroke in one direction to release said latch, and a cable connected with said lever for releasing said latch and moving said shifting member in the direction away from the belt.

23. A belt shifter comprising a frame located opposite one edge of a belt, a shifting member movably mounted on said frame, means on said frame for supporting said belt thereon, means for moving said shifting member for moving the belt into position on said supporting means, a spring pressed latch adapted automatically to hold said shifting member against movement away from the belt, a lever adapted by a stroke in one direction to release said latch, a cable connected with said lever for releasing said latch and moving said shifting member in the direction away from the belt, and a second cable also operatively engaging said lever for moving the shifting member toward said belt.

In testimony whereof I have signed my name to this specification in the presence of two subscribing witnesses.

EMERALD E. JONES.
